UNITED STATES PATENT OFFICE.

WILLIAM J. LUTHMERS, OF OLNEY, ILLINOIS.

PIANO-ACTION FLANGE.

1,157,629.

Specification of Letters Patent. Patented Oct. 19, 1915.

Application filed August 3, 1914. Serial No. 854,762.

To all whom it may concern:

Be it known that I, WILLIAM J. LUTHMERS, a citizen of the United States, residing at Olney, in the county of Richland and State of Illinois, have invented certain new and useful Improvements in Piano-Action Flanges; and I do declare the following to be a full, clear, and exact description of the invention, such as will enable others skilled in the art to which it appertains to make and use the same.

My invention relates to piano actions, but more especially to flanges used in conjunction with the latter to pivotally support the hammer and damper in their proper position.

One object of this invention is to provide a device of this character having means for partially enveloping the transverse rails of a piano which will prevent horizontal movement on the part of said flange.

A further object is to provide means for the removal of the hammer without necessitating the withdrawal of the flange.

A still further object is to provide a unique means for retaining the hammer and damper springs in proper position which will at the same time permit of their ready removal.

A still further object is to simplify the construction of the parts whereby they may be made more accessible when repairing is necessary.

With these and other objects in view my invention consists of certain details of construction and combination and arrangement of parts which will be more particularly pointed out and claimed.

In the accompanying drawing in which corresponding parts are designated by similar reference numerals Figure 1 is a vertical section taken across the rails of the piano action and illustrating the damper and hammer butt connected by my improved flange. Fig. 2 is an enlarged transverse vertical section of the hammer butt, damper and rail, illustrating my improved flange applied to the latter, and positioned to pivotally retain said hammer and damper. Fig. 3 is a similar view showing the flange members separated and in position to receive the pin of the hammer butt. Fig. 4 is a plan view partly in section. Fig. 5 is a detailed vertical section taken on the line 5—5 of Fig. 2.

In its present exemplification my improved flange comprises a substantially U-shaped lower plate 1, formed of any suitable resilient metal, and adapted to be seated upon and partially embrace the longitudinally extending tongue 2 on the main rail 2' whereby any horizontal movement on the part of said body 1 is prevented as clearly shown in Figs. 3 and 4. Extending laterally from the body 1 are the two arms 3 and 4 which are reduced at their outer portion as at 5.

Overlying the U-shaped plate 1, in fact the latter may be said to telescope therein, is a similar shaped upper plate 6 formed of the same material, and carrying laterally projecting arms 7 and 8 which overlie the arms 3 and 4 and have their outer portion so reduced as to make the configuration thereof identical to that of the underlying arms 3 and 4. The meeting edges of two of these arms 3 and 7 are united, and immediately adjacent their united edges they are formed with the transverse opening 9, which receives the pivotal pin 10 in the damper 11, whereby the latter may be pivotally supported in its proper position as will be readily understood.

As it is frequently desirable to detach the hammer 12 for repairing or other purposes without disturbing the damper 11, the inner faces of the arms 4 and 8 which by reason of the resiliency of the plates are normally separated, have formed in their adjacent faces contiguous to the extremities thereof transversely extending channels 13. These channels coat when the arms 4 and 8 are brought together, so as to completely house and pivotally retain the pin 13' carried by the hammer butt 14.

To permanently maintain the flange in its adjusted position upon the rail 2, the telescoping U-shaped plates 1 and 6 are formed with a centrally arranged registering opening 15, through which and into said rail 2 there passes a screw 16. With the plates arranged in this manner and the screw 16 passing therethrough as aforesaid, adjusting the latter will cause said plates as well as the arms carried thereby to be pressed into contact, so that if the pin 13 of hammer butt 14 is disposed between the arms 4 and 8, in alinement with the channels therein, when said arms have been fully brought together the pin 13 will be entirely inclosed

by the walls of channels 12, and thereby suitably pivot the hammer butt 14. In view of the above it will be apparent that adjusting the screw 16 will cause the arms 8 and 4 to be brought in to or out of engagement as the case might be thus permitting the hammer to be removed or brought into proper position whenever desired.

In order that the damper and hammer 10 springs may be easily removed and replaced when broken as well as to avoid the necessity of a bridle ribbon and wire as well as an additional hammer spring supporting rail, I provide the sides of the U-shaped 15 plates 1 and 6 with registering openings 17 and 17'. The former 17 being in one side thereof, and the other 17' being formed in the opposite side, and in diagonal relation to the opening 17 as clearly shown, in Fig. 4. 20 Into these openings are fitted the lower extremities of the springs 18, the upper extremities thereof contacting with the damper and hammer in the usual manner. The simplicity of this construction allows a spring 25 to be easily replaced when desirable, and at the same time prevents the separation of the upper and lower plates should the screw 16 be accidentally loosened through vibration or other causes.

30 It will thus be apparent that I have effected a flange which is simple, inexpensive to construct, efficient in operation and one which will greatly reduce the cost of repairing.

35 From the foregoing description, taken in connection with the accompanying drawings, the construction and operation of the invention will be readily understood without requiring a more extended explanation.

40 Various changes in the form, proportion and the minor details of construction may be resorted to, without departing from the principle or sacrificing any of the advantages of the claimed invention.

45 Having thus described my invention, what I claim is:

1. A flange for piano actions comprising upper and lower overlying resilient plates U-shaped intermediate their ends, each of 50 said plates being formed with a centrally arranged opening, the openings in the respective plates being disposed in alinement, laterally extending arms carried by the extremities of said plates, the former being re-

duced at the outer portion thereof, one pair of said arms having the extremities united and formed with a transversely extending opening to form an eye and the other pair thereof being free and formed with coacting 55 grooves in the adjacent face of their extremities.

2. A flange for piano actions comprising upper and lower overlying resilient plates U-shaped intermediate their ends, each of 60 said plates being formed with a plurality of

openings, one of the latter being disposed in a plane at right angles to that of the others, the openings in the respective plates being disposed in alinement, laterally extending arms carried by the extremities of said 70 plates, the former being reduced at the outer portion thereof, one pair of said arms having the extremities united and formed with a transversely extending opening to form an eye and the other pair thereof being free and 75 formed with coacting grooves in the adjacent face of their extremities.

3. A flange for piano actions comprising a resilient plate bent intermediate its ends to form an eye, the free ends of said plate 80 being brought to an overlying position and U-shaped intermediate said eye and the extremities of said free ends, said U-shaped portion being formed with a plurality of openings, one of the latter being disposed in 85 a plane at right angles to that of the others, the openings in the respective U-shaped portions being disposed in alinement, and oppositely disposed laterally extending arms formed by said U-shaped portion of the 90 plate, said arms having the outer portion thereof reduced, the free ends of said plate forming one of said arms having transversely extending grooves in the adjacent surfaces of their extremities to coact substantially as and for the purpose set forth. 95

4. The combination with a main rail, a longitudinally extending rib thereon, a hammer, a damper, and springs to actuate said hammer and damper; of upper and lower 100 U-shaped resilient plates seated upon said rib, each of said plates having therein a centrally arranged aperture, the apertures in the respective plates being disposed in alinement, a screw passing through said 105 apertures and into said rail; laterally extending arms carried by said plates, the former being reduced at the outer ends thereof, one pair of said arms having their extremities united and formed with an eye, 110 the other pair being free and formed at their extremities with coacting channels, a pin extending through said damper and said eye whereby to pivotally support said damper, and a pin extending through said 115 hammer and inclosed by the walls of said channels when said plates have been pressed together by said screw, substantially as and for the purpose set forth.

5. A flange for piano actions comprising 120 upper and lower overlying resilient plates U-shaped intermediate their ends, each of said plates being formed with an opening, the openings in the respective plates being disposed in alinement, laterally extending arms carried by the extremities of said 125 plates, one pair of said arms having their extremities united and formed with a transversely-extending opening to form an eye and the other pair thereof being free and 130

formed with coacting grooves in the adjacent faces of their extremities substantially as and for the purpose set forth.

6. A flange for piano actions comprising upper and lower overlying resilient plates U-shaped intermediate their ends, said plates being formed with a plurality of openings, the plane of one of the latter being in a plane at right angles to that of the others, the openings in the respective plates being disposed in alinement, laterally extending arms carried by the extremities of said plates, one pair of said arms having their

extremities united and formed with a transversely extending opening to form an eye 15 and the other pair thereof being free and formed with coacting grooves in the adjacent face of their extremities substantially as and for the purpose set forth.

In testimony whereof I have hereunto set 20 my hand in presence of two subscribing witnesses.

WILLIAM J. LUTHMERS.
